Primary Examiner — Susan Moon Lee(74) *Attorney, Agent, or Firm* — Eleanor Musick; Torrey Pines Law Group, PC(57) **CLAIM**

The ornamental design for a hanging bird feeder, as shown.

DESCRIPTION

FIG. 1 is a side perspective view of the hanging bird feeder showing my new design;

FIG. 2 is a first side elevational view of the hanging bird feeder;

FIG. 3 is a second side elevational view of the hanging bird feeder;

FIG. 4 is a third side elevational view of the hanging bird feeder;

FIG. 5 is a top plan view of the hanging bird feeder; and,

FIG. 6 is a bottom plan view of the hanging bird feeder. The broken line showing of a section of a hanging cable is included for the purpose of illustration only and forms no part of the claimed design.
